CLAIM

The ornamental design for an electronic cigarette assembly, as shown and described.

DESCRIPTION

FIG. 1 is a front, top, left perspective view of an electronic cigarette assembly showing my new design shown as component 1 removed from the assembly in FIGS. 14 -21 for clarity of disclosure;

FIG. 2 is a front, bottom, right perspective view thereof;

FIG. 3 is a front elevational view thereof;

FIG. 4 is a top plan view thereof;

FIG. 5 is a bottom plan view thereof;

FIG. 6 is a front, top, left perspective view of the electronic cigarette assembly showing my new design shown as component 2 removed from the assembly in FIGS. 14 -21 for clarity of disclosure;

FIG. 7 is a front, bottom, right perspective view thereof;

FIG. 8 is a front elevational view thereof;

FIG. 9 is a rear elevational view thereof;

FIG. 10 is a left-side elevational view thereof;

FIG. 11 is a right-side elevational view thereof;

FIG. 12 is a top plan view thereof;

FIG. 13 is a bottom plan view thereof;

FIG. 14 is a front, top, left perspective view of the electronic cigarette assembly showing my new design where component 1 and component 2 are shown in an assembled state of use;

FIG. 15 is a front, bottom, right perspective view thereof;

FIG. 16 is a front elevational view thereof;

FIG. 17 is a rear elevational view thereof;

FIG. 18 is a left-side elevational view thereof;

FIG. 19 is a right-side elevational view thereof;

FIG. 20 is a top plan view thereof; and,

FIG. 21 is a bottom plan view thereof.

The broken lines in the drawings depict portions of the electronic cigarette assembly that form no part of the claimed design.

The rear, left-side, and right-side elevational views of an electronic cigarette assembly showing my new design shown as component 1 removed from the assembly in FIGS. 14 -21 are the same as the front elevational view thereof, and thus are omitted.
